FIG. 1.

FIG. 2.

Charles J. Messer
^{INVENTOR}
by
Howard P. Dinson
^{ATTORNEY.}

UNITED STATES PATENT OFFICE.

CHARLES J. MESSEY, OF SYRACUSE, NEW YORK.

DESIGN FOR A CANDLE.

53,043.

Specification for Design.

Patented Mar. 4, 1919.

Application filed April 5, 1918. Serial No. 226,957. Term of patent 7 years.

To all whom it may concern:

Be it known that I, CHARLES J. MESSEY, a citizen of the United States, residing at the city of Syracuse, in the county of Onondaga and State of New York, have invented a new, original, and ornamental Design for Candles, of which the following is a specification, reference being had to the accompanying drawing, forming part thereof.

Figure 1 is a top plan and Fig. 2 a side

elevation of a candle showing my new design.

What I claim is:

The ornamental design for a candle as shown.

CHARLES J. MESSEY.

Witnesses:

ALICE M. CANNON,
SYBIL WARNER.
